UNITED STATES PATENT OFFICE.

GEORGE E. AMES, OF SAN FRANCISCO, CALIFORNIA.

ROCK-CRUSHER.

SPECIFICATION forming part of Letters Patent No. 400,157, dated March 26, 1889.

Application filed August 8, 1888. Serial No. 282,257. (No model.)

To all whom it may concern:

Be it known that I, GEORGE E. AMES, of the city and county of San Francisco, State of California, have invented an Improvement in 5 Rock-Crushers; and I hereby declare the following to be a full, clear, and exact description of the same.

My invention relates to that class of rock-crushers in which a movable or vibrating jaw 10 operates against an opposing fixed jaw, the rock being crushed between the two jaws; and my invention consists in the novel details of construction and arrangement, which I shall hereinafter fully describe and claim.

15 The object of my invention is to increase the capacity and strength of the machine, to reduce its weight, and to provide simple and reliable means for effecting the several adjustments.

20 Referring to the accompanying drawings for a more complete explanation of my invention, Figure 1 is a side elevation of the crusher. Fig. 2 is a vertical section of the same. Fig. 3 is a plan.

25 A are the frame-castings of the machine, connected together by longitudinal bolts B. In one end of the machine is secured the fixed jaw C, opposing which is the movable or vibrating jaw D, which is pivoted or journaled 30 at E at its upper end.

F is the drive-shaft of the machine, having fly-wheels f and the usual fast and loose pulleys, f'.

35 G is an eccentric on the shaft F, from which depends the connecting-rod H.

I is an arm having its rear end seated in the forward side of the connecting-rod H and its forward end seated in the back of the movable jaw.

40 J is an arm having its forward end seated in the back of the connecting-rod H and its rear end seated in the transverse support K, consisting of a bar which is mounted and adapted to be adjusted upon the projecting 45 rear ends of the bolts B back of the rear casting of the frame. Nuts b are fitted on the bolts at their rear ends, said nuts being set up against the back of the support to effect its proper adjustment.

50 L is the take-up rod, the forward end of which is connected with the base of the mov-

able jaw, and it has on its rear end outside of the frame a steel spring, M. The bolts B are shouldered at b' just back of the frame, and have nuts b² on their forward ends, 55 whereby they may be tightened up. Their projecting rear ends form supports for the support.

This is the general construction of the machine, and its operation is obvious. As the 60 connecting-rod H moves up and down by the motion of the eccentric, it raises the forward arm, I, in its bearings and causes the movable jaw to vibrate on its pivotal center, thereby effecting the crushing of the rock between 65 the jaws. By setting up the nuts b so as to move the support K forward the wear on all the arms is properly taken up and the opening between the jaws is adjusted with respect to its capacity. The working strain is 70 taken by the bolts B.

In the face of the fixed jaw C is fitted the wearing-plate c, and in the face of the movable jaw D is fitted the wearing-plate d. These are held in place by means of keys c' 75 d', as shown, which enables them to be easily replaced when necessary. The wear on the journal E of the movable jaw is taken up by means of a sliding gib, N, which is fitted in a recess in the head of the jaw and presses 80 against the journal, said gib being set up to place by means of the set-screw n. The bearings of the arms I and J are formed of steel blocks O, properly let into their seats and held in place by means of set-screws o. These 85 blocks receive all the wear, and can be readily taken out and replaced when necessary. The bearings of the arms and other journals and joints of the machine are kept properly lubricated by means of the pipes P, the lower 90 ends of which are fitted into the oil-holes below, and their upper ends extend above the frame of the machine, so as to be easily reached for the purpose of pouring the oil into them. The connecting-rod H is fitted to 95 the eccentric by means of the cap-piece h, which embraces the top of the eccentric and is secured to the rod by means of the bolts h'. This construction provides for the easy adjustment and substitution of the rod. The 100 take-up rod L is secured by a link, l, to the eyebolt Q, which is let into the base of the

movable jaw, and is secured therein by a nut, *q*. This construction renders the eyebolt readily removable when necessary.

Having thus described my invention, what 5 I claim as new, and desire to secure by Letters Patent, is—

In a rock-crusher, the frame-castings, the fixed jaw, the movable jaw, and the means for operating said movable jaw, consisting of 10 an eccentric, the depending connecting-rod, and the arm between said rod and the movable jaw, in combination with the longitudinal bolts passing through the castings for holding them together and receiving the

strain, said bolts having shoulders *b'*, projecting rear ends, nuts *b²*, the sliding support *K*, mounted on the projecting rear ends of the bolts outside of the frame-castings, the nuts for moving said support *K*, and the arm *J* between the connecting-rod and the support *K*, 20 substantially as herein described.

In witness whereof I have hereunto set my hand.

GEORGE E. AMES.
